MEDICAL INSTRUMENT FOR MEASURING
BONE DENSITY

Robert E. Olson, Glen Ellyn, and Frederick W. Thompson, Wilmette, Ill., assignors to Packard Instrument Company, Inc., Downers Grove, Ill., a corporation of Delaware

Filed Apr. 24, 1969, Ser. No. 16,882

Term of patent 14 years

Int. Cl. D24—02

U.S. Cl. D83—1

FIG. 1 is a front perspective view of a medical instrument for measuring bone density embodying our new design;

FIG. 2 is a rear perspective view thereof; and

FIG. 3 is a bottom plan view thereof.

In FIGS. 1 and 2 of the drawing, the top central cutout portion of the instrument is plain in appearance throughout.

We claim:

The ornamental design for a medical instrument for measuring bone density, substantially as shown and described.
